UNITED STATES PATENT OFFICE.

MARIO PERUZZI, OF WILKES-BARRE, PENNSYLVANIA, ASSIGNOR TO PLANTERS NUT & CHOCOLATE CO., OF WILKES-BARRE, PENNSYLVANIA.

DESIGN FOR A GLASS JAR.

Application filed February 21, 1928. Serial No. 25,509. Term of patent 14 years.

To all whom it may concern:

Be it known that MARIO PERUZZI, a citizen of United States, residing at Wilkes-Barre, in the county of Luzerne and State of Pennsylvania, has invented a new, original, and ornamental Design for a Glass Jar, as shown in the accompanying drawing and described in the following specification.

Fig. 1 shows a plan view; Fig. 2 a side perspective view; and Fig. 3 an end view of the new design.

I claim:

The ornamental design for a glass jar as shown.

MARIO PERUZZI.
